UNITED STATES PATENT OFFICE.

JOHN SCOTT, OF NICHOLASVILLE, KENTUCKY.

DESIGN FOR A BEDSTEAD.

SPECIFICATION forming part of Design No. 26,597, dated February 2, 1897.

Application filed November 19, 1896. Serial No. 612,767. Term of patent 3½ years.

To all whom it may concern:

Be it known that I, JOHN SCOTT, of Nicholasville, in the county of Jessamine and State of Kentucky, have made a new and original 5 Design for a Bedstead, of which the following is a specification.

My invention relates to a design for a bedstead.

It relates to the entire configuration of the 10 bedstead.

My invention relates particularly to a bedstead as illustrated in the accompanying drawings in which the figure represents a perspective view of a bedstead embodying my 15 design.

The leading features of my design consist in ornamental panels forming the head and foot boards of a bedstead of the configuration and ornamentation shown, which I will now

proceed to describe in detail. Said head and 20 foot boards are provided with a background or field, appearing as interwoven strands, the outer edges of said field formed in alternating curves and angles. The center of said field is ornamented by an eight-pointed star. 25 The corners of the background or field are ornamented by scrolls.

Having thus described my invention, what I claim as new, and desire to secure by Letters Patent, is—

The design for a bedstead as herein shown and described.

In testimony whereof I hereunto affix my signature in the presence of two witnesses.

JOHN SCOTT.
